UNITED STATES PATENT OFFICE

136,395

DESIGN FOR AN ENGINEER'S SCALE TEMPLATE OR THE LIKE

Joseph E. Deckman, Ambler, Pa., assignor to
Keasbey & Mattison Company, Ambler, Pa., a
corporation of Pennsylvania

Application July 2, 1943, Serial No. 110,585

Term of patent 7 years

To all whom it may concern:

Be it known that I, Joseph E. Deckman, a citizen of the United States, residing at Ambler, in the county of Montgomery and State of Pennsylvania, have invented a new, original, and ornamental Design for Engineer's Scale Template or the like, of which the following is a specification, reference being had to the accompanying drawing forming part thereof, in which:

Fig. 1 is a front elevational view of an engineer's scale template showing my new design; and

Fig. 2 is a side edge view thereof.

I claim:

The ornamental design for an engineer's scale template or the like, substantially as shown.

JOSEPH E. DECKMAN.
